UNITED STATES PATENT OFFICE.

JAMES DUVALL, OF CAMAS, WASHINGTON.

PNEUMATIC PRESS-FEEDING MEANS.

1,207,149.

Specification of Letters Patent.

Patented Dec. 5, 1916.

Application filed December 27, 1915. Serial No. 68,743.

To all whom it may concern:

Be it known that I, JAMES DUVALL, a citizen of the United States, and a resident of Camas, county of Clark, and State of Washington, have invented a new and useful Improvement in Pneumatic Press-Feeding Means, of which the following is a specification.

My invention relates to mechanism which automatically and by means of air suction feeds the undermost sheet, envelop, bag, or the like, from a pile or vertical stack of material to other means for operating thereon, and more particularly relates to the feeding of all sizes of paper bags to a bag printing press. Its object is to provide a much simpler and more dependable means of feeding such stacked material to the press, one unit at a time, uniformly and rapidly. It does away with the carrier belts and nipper devices so common in such press feeding means thus greatly simplifying same and avoiding the complicated mechanisms that have heretofore been such a source of trouble and delay in the operation of the press.

The accompanying drawings, forming a part hereof, illustrate a common form of bag printing press, with the usual plate and impression cylinders and an adjustable rack, open on the bottom to allow the bags to be fed from underneath, and with the description herein, make clear the principles of my invention and the best mode in which I have embodied those principles in applying my feed mechanism to this bag printing machine.

Figure 1 is a side elevation of the press, showing diagrammatically the elements of the feed mechanism. Fig. 2 is a plan, with the bag rack 6 omitted. Fig. 3 is an end view showing location of air valve 11, suction hose 12, suction pipe 13, and the cams 8 and 9 on cam shaft 16. Fig. 4 is a perspective of the hollow, slotted feeder roll 3, with opening 3^a therein, one of the most important features of my invention. Fig. 5 is a side elevation with the front frame part F removed and shows a bag just being engaged by the slotted feeder roll 3. Fig. 6 is a perspective detail showing relation between the air valve 11, its cam 9 and the suction box 5, its actuating lever 7, cam 8 and spring 18. Fig. 7 is a perspective detail of air valve 11 and its cam 9, showing lever 10 in elevated position and air shut off after passage of cam. It will be noted that the cam segment

is abrupt at 9^a, shutting off the air instantly. Fig. 8 is a plan of the suction box 5 showing the orifices 5^a and Fig. 9 is a side view of the suction box, showing suction hose connection on the bottom.

The top roll 1, Figs. 1 and 5, is the type or plate cylinder and the bottom roll 2 is the impression cylinder, it being the object of all the various feed mechanisms to continuously feed these printing rolls with the material to be operated upon. Figs. 1 and 5 show very plainly how this is accomplished by my mechanism. The bags to be printed are placed in the usual form of adjustable bag rack 6 by the operator, one on top of the other, the forward part of the bottom of the rack being open to allow the undermost bag to be pulled from the pile. Fig. 1 shows the suction element 5, with its suction orifices 5^a, Figs. 2 and 8, in engagement with the forward and bottom part of the lowest bag of the pile 17 that has been stacked in the feed rack. The cam 9, Figs. 1 and 6, is so adjusted in relation to lever 10, of the cut-off air valve 11, that at this instant it presses down the lever and opens the valve, the suction becoming active and the bottom bag is thus caused to adhere firmly to the suction box 5. The cam 8 now engages pin 7^a, Fig. 6, of lever 7, which is mounted on rocker shaft 15 together with the suction box 5, and the latter is moved into the position shown in Fig. 5, the forward end of the bottom bag being pulled from the pile 17. Just as the end of the bag is thus pulled clear of the rack it enters the slotted opening 3^a in the hollow feeder roll 3, whose rotation is so timed in relation to the suction box movement that this slot or opening is always in the proper position to receive the end of the bag. The cam 8 has not quite finished its throw, the suction box and bag being tilted a little lower and the rotating hollow feeder roll 3, by means of the upper edge of the opening 3^a engaging the end of the bag, depresses same until it is caught in the pinch between the rolls 3 and 4, the former roll being in contact with the impression roll 2, but the small idler roll 4 only being in contact with the slotted feeder roll 3. The cam 9 that actuates the lever 10 of the air cut-off valve 11, is so timed and designed, 9^a, Fig. 7, that it abruptly and instantaneously releases the air valve spring thus shutting off the suction just as the forward end of the bag enters the nip of the

feeder rolls 3 and 4 and thus the bag is free to be fed between the slotted roll 3 and the impression cylinder 2 and thence it passes between the type or plate cylinder 1 and impression cylinder 2. When the feeder rolls 3 and 4 take the bag from the suction box, the cam 9 has passed its period of greatest throw and the coil spring 18, shown in Fig. 6 and partially in Fig. 1, and which exerts a constant tension, pulls on the lever or arm 7, attached to the rocker shaft 15, and the suction box, mounted on this same rocker shaft, is restored to its original position into engagement with the bottom bag of pile 17 and cam 9 again depresses lever 10 and the suction again becomes active and the movement repeats itself with rapidity and precision.

While the above embodies a successful form of my feed mechanism, increasing the capacity of the press fully twenty-five per cent., I realize that many minor changes may be made therein and so do not wish to limit myself to the precise construction shown. For example, the suction box, impression and plate rolls and the hollow slotted feeder roll may be so proportioned and arranged as to eliminate the small idler feeder roll 4, but still this would not depart from the spirit of my invention which claims the slotted feeder roll 3 as broadly new in press feeding mechanisms.

I claim,

1. In a pneumatic feed for presses with the usual plate and impression cylinders and an adjustable rack to hold a pile of material so that it can be fed to the press from underneath, a suction element whose orifice is directly under the forward end of the feed rack, means to swing the mouth of the suction element vertically toward and away from the bottom of the feed rack, a cut-off air valve controlling the suction and means for opening and closing same at proper intervals, a hollow, slotted feeder roll whose periphery is wholly outside of the path of the suction element, but is in contact with the impression cylinder, and which engages, when the suction element pulls it downward, the entire forward end of the undermost unit of the pile of material that is being fed to the press and an idler roll in contact with the rotating slotted feeder roll which cooperates with it when the suction releases, to forward the material between the plate and impression cylinders.

2. In a pneumatic feed for presses with the usual plate and impression cylinders and an adjustable rack to hold a pile of material so that it can be fed to the press from underneath, a suction element whose orifice is directly under the forward end of the

feed rack, means to swing the mouth of the suction element vertically toward and away from the bottom of the feed rack, a cut-off air valve controlling the suction and means for opening and closing same at proper intervals, a hollow, slotted feeder roll whose periphery is wholly outside of the path of the suction element, but is in contact with the impression cylinder, and which engages, when the suction element pulls it downward, the entire forward end of the undermost unit of the pile of material that is being fed to the press causing same to enter the nip between it and the impression cylinder and be passed to the printing cylinders.

3. In a pneumatic feed for presses with the usual type and impression cylinders, a hollow, longitudinally slotted feeder roll in contact with the impression cylinder, located just forward of the pinch between the plate and impression cylinders.

4. In a pneumatic feed for presses of the type described, a hollow, longitudinally slotted feeder roll whose periphery is wholly outside of the path of the suction element, but is in contact with the impression cylinder, located just forward of the pinch between the plate and impression cylinders and an idler feeder roll in contact with the slotted feeder roll just forward of the pinch between it and the impression cylinder.

5. In a press comprising a plate or type cylinder and an impression cylinder, a suction element attached to a rocker shaft, with the mouth of the suction box directly underneath the feed rack, a lever or arm affixed to said rocker shaft, a cam which actuates said lever and said suction element, a spring attached to lever which tends to bring it and the suction box into their original position, as air valve, a lever on air valve, a cam which engages said air valve lever to open and close the valve at the proper intervals, a rotating longitudinally slotted feeder roll whose periphery is wholly outside of the path of the suction element, but is in contact with the impression cylinder and an idler feeder roll in contact with the slotted feeder roll.

6. In feeding means for a press comprising a type cylinder and an impression cylinder, a suction element and means for actuating same, in combination with a rotating longitudinally slotted hollow feeder roll whose periphery is wholly outside of the path of the suction element, but which is in contact with the impression cylinder.

JAMES DUVALL.
